UNITED STATES PATENT OFFICE.

RALPH A. K. TRABER, OF ST. LOUIS, MISSOURI.

NUTCRACKER.

1,087,617.

Specification of Letters Patent. Patented Feb. 17, 1914.

Application filed January 31, 1913. Serial No. 745,311.

To all whom it may concern:

Be it known that I, RALPH A. K. TRABER, a citizen of the United States, residing at the city of St. Louis and State of Missouri, have invented certain new and useful Improvements in Nutcrackers, of which the following is a specification.

This invention relates to nutcrackers, and has for its primary object to provide an improved nutcracker that is simple to construct, inexpensive to manufacture, and effective in operation.

Another object of the present invention resides in the provision of a nutcracker having an adjustable stop or jaw that can be quickly and easily set in proper relation to the nut to be cracked, and, also, a cracking plunger or jaw that has a relatively long stroke so that same effectively cracks any kind of a nut without the necessity of resetting the adjustable stop or jaw.

A further object of the present invention consists in the provision of a nutcracker in which the cracking plunger or jaw is connected to the operating lever in such manner that the greatest power is obtained during the initial cracking of the nut.

Further, the present invention consists of the novel features of construction and arrangement of parts hereinafter more fully described and pointed out in the claims.

In the accompanying drawings forming part of this specification, in which like numbers of reference denote like parts wherever they occur, Figure 1 is a perspective view of a nutcracker embodying the present invention; Fig. 2 is a side elevation of same, partly in section; Fig. 3 is an end elevation of same; and Fig. 4 is a side elevation of an alternative form of the present invention.

In the drawings, the frame or support may be a one-piece casting as illustrated or constructed in any desired manner. The upper part of the frame or support is formed with somewhat of an inverted U-shaped cross-sectional configuration to afford a housing 2 for the cracking plunger 3. A vertical arm 1 borne by the frame or support has a rearwardly extending horizontal part 4 which projects below the housing 2 at a sufficient distance therefrom to receive the top of a table 5 or other support between same and the housing 2 and contains a screw-threaded opening which receives a clamp-screw 6 or the like for attaching the nutcracker to said table or support 5. The

plunger 3 extends through an opening 7 in the housing 2 and has an enlarged outer end 8, which contains a socket or depression 9 for the reception of either an end or a side 60 of a nut (not shown) to be cracked. The inner end of the plunger 3 is pivotally connected at 10 to and between the bifurcations 11 on the lower end of the operating lever 12, which is pivotally attached to and between the side walls of the housing 2 by a pin 13 or other suitable means. The lever 12 extends through an opening 14 in the housing 2, and may bear a handle 15 of any size or shape, the opposite end walls 16 and 17 of said opening 14 being preferably arranged so as to limit the movement of the lever 12 and being spaced at sufficient distance apart to permit said lever to have ample movement to produce a relatively 75 long stroke of the plunger 3. In the present instance, when the lever 12 is rocked counter-clockwise, Fig. 2, on its pivot 13 from engagement with the wall 16 of the opening 14 to engagement with the wall 17 of said 80 opening, same will move the plunger 3 outwardly through the opening 7 in the housing 2 to the position depicted in dotted lines, while reverse movement of the lever 12 will draw the plunger inwardly and restore it 85 to normal position.

A block or jaw 18 is located directly in front of the outer end 8 of the plunger and is adjustably supported on an extension or forwardly projecting arm 19 formed on the 90 vertical arm 4 of the frame or support, so as to be movable toward and away from the plunger 3 in substantially the same vertical plane with said plunger, said extension or arm 19 being preferably reinforced by a 95 web 20, so as to have a T-shaped cross-sectional configuration, and having a plurality of notches 21 formed transversely in its upper surface. Flanges 22 projecting downwardly and inwardly from the sides of the 100 block 18 underlie the side edges of the extension or arm 19 and thereby not only hold the block in place on said extension or arm, but, also, guide the movement of said block, and a handle 23 borne by said block affords 105 a means for moving same along said extension or arm, said handle being preferably provided with an opening 24 to receive a finger or thumb in an obvious manner. In the face of the block 18 toward the plunger 110 3 there is formed a socket or depression 25, which is located directly in front of

and in alignment with the socket 9 in the outer end 8 of said plunger, so that when a nut is placed in proper position to be cracked between the plunger 3 and the block 18, the socket 9 in said plunger will receive one end or side of the nut while the socket 25 in said block will receive the opposite end or side of the nut.

A heel or projection 26 borne by the block 18 seats in a notch 21 in the extension or arm 19 and thereby holds said block from movement when a nut is pressed against the latter by the outward movement of the plunger 3, with the result of causing the nut to be cracked. It will be observed that ample space is left between the flanges 22 of the block 18 and the lower face of the extension or arm 19, in order to allow the block 18 to be raised sufficiently to withdraw the heel 26 from a notch 21 so that the block can be moved along the extension or arm and set with the heel seating in another notch 21. By this arrangement, the distance between the block 18 and the plunger 3 can be increased or decreased for different sizes of nuts. The notches 21 are preferably arranged so that, when it is desired to move the block 18 toward the plunger 3, it is unnecessary to raise the block so as to withdraw the heel 26 from a notch 21, for the reason that during such movement of said block the notches 21 will allow the heel to ride thereover, whereas, when it is desired to move the block 18 away from the plunger 3, it is necessary to raise the block sufficiently to withdraw the heel 26 from a notch 21 preparatory to such movement. A pin or projection 27 borne by the extension or arm 19 adjacent to the end thereof prevents the block from sliding off said extension or arm.

In order to crack a nut, the lever 12 is moved to the position depicted in full lines, Fig. 2, if not in such position, so as to retract the plunger 3, and then the nut is placed with an end or a side thereof in the socket 9 in the outer end 8 of said plunger, after which the block 18 is moved toward the plunger 3, in the manner hereinabove described, until the opposite end or side of the nut seats or nearly seats in the socket 25 in said block and the heel 26 of said block seats in a notch 21 in the extension or arm 19, whereupon the lever 12 is rocked counter-clockwise, with the result of causing the plunger 3 to move outwardly and press the nut against the block 18 with sufficient force to crack same. By moving the lever in the opposite direction so as to retract the plunger 3 after the nut has been cracked, the cracked nut may then be removed from between said plunger and the block.

It will be observed that, when the lever 12 occupies its normal position so as to hold the plunger 3 in its retracted position, the

pivotal connection 10 stands substantially directly behind the pivotal pin 13, the advantage of this arrangement being that, during the initial movement of the lever 12, although the plunger 3 is moved relatively slow, the greatest power is transmitted to same for the initial cracking of the nut. The fact that the lever 12 imparts a relatively long stroke to the plunger 3 as hereinabove described enables the operator to crack any kind of a nut with but one movement of the lever and without the necessity of resetting the block 18. This feature is of particular advantage when cracking nuts of one kind or of substantially the same size, for the reason that the block 18 can be set at a predetermined distance from the outer end of the plunger 3 so as to allow the nut to be placed with an end or a side thereof in the socket 25 in said block, after which the lever 12 is first moved so as to bring the outer end of the plunger 3 against the opposite end or side of the nut and then is moved farther in the same direction, with the result of causing the plunger to crack the nut against the block. It will be evident that, when the nutcracker is used for cracking mixed nuts or nuts of various sizes, the block 18 can be easily and quickly adjusted as hereinabove described, in order to increase or decrease the distance between same and the plunger 3 for the different sizes.

In the alternative form of the invention depicted in Fig. 4, the housing 2 is omitted entirely and the lever 12 is pivotally attached at 13 to an upright 28 borne by the frame or support 1'. The plunger 3 extends through an opening 29 in a guide 30 borne by the frame or support 1', and is pivotally attached at 10 to the lever 12 in such manner that, when said lever occupies its normal position to hold the plunger 3 in its retracted position, the pivotal connection 10 stands approximately below the pivotal pin 13, so as to produce a relatively faster movement of said plunger during the initial movement of the lever. The cam surface 31 on the plunger 3 adjacent to the outer end thereof engages with the bottom of the opening 29 in the guide 30 when the plunger is moved outwardly, thereby causing the outer end of said plunger to move substantially parallel to the extension or arm 19.

Minor changes in the structural details and arrangement of parts may be made without departing from the nature and spirit of the present invention.

I claim:

1. A nut cracker consisting of a frame having a central vertical arm that has its lower portion formed with a rearwardly extending horizontal part, means borne by the said horizontal part to clamp the frame onto a support, a horizontal member extend-

ing rearwardly of the arm and having its lower portion for seating engagement on the support, said member having a horizontal guide opening at its front, a horizontal 5 plunger in the guide opening, a lever pivoted to the rear of the support and to the plunger, a horizontal arm extending forwardly of the vertical arm and connected to the latter, and a jaw on the horizontal arm 10 for coöperation with the plunger.

2. A nut cracker consisting of a frame having a central vertical arm that has its lower portion formed with a rearwardly extending clamp carrying horizontal part, to 15 clamp the frame onto a support, a horizontal housing of inverted U-shape in cross-section at the upper end of the arm having its free edges for engagement with the top face of the support, the ends of the housing

being vertically disposed and closed, the 20 front end of the housing having a horizontal guide opening and the rear end having an elongated opening, a plunger within the housing having its front end extending through said guide opening, a lever having 25 one end extending through the opening in the housing top and being pivotally connected to the housing and to the rear end of said plunger, a horizontally disposed arm connected to and extending forwardly of the 30 vertical arm, and a jaw on the horizontal arm for coöperation with the plunger.

In testimony whereof I hereunto affix my signature in the presence of two witnesses.

RALPH A. K. TRABER.
